UNITED STATES PATENT OFFICE.

GUSTAV EIRICH, OF HARDHEIM, GERMANY.

MIXING AND KNEADING MACHINE FOR EARTHY AND MINERAL MATERIALS.

1,155,712.

Specification of Letters Patent.

Patented Oct. 5, 1915.

Application filed September 16, 1912. Serial No. 720,581.

To all whom it may concern:

Be it known that I, GUSTAV EIRICH, a subject of the Grand Duke of Baden, residing at Hardheim, in the Grand Duchy of Baden, German Empire, have invented certain new and useful Improvements in Mixing and Kneading Machines for Earthy and Mineral Materials, of which the following is a specification.

10 The present invention refers to improvements in mixing or kneading devices such as are used for mixing earthy or mineral materials although I do not specifically confine myself to the applications referred to.

15 The object of my invention is to provide an arrangement in which the mixing elements are efficiently protected against the effects of strains or stresses produced by obstructions in the materials being mixed.

20 My improvement comprises substantially horizontally disposed sleeves in which shafts are journaled, said shafts having portions bent at angles and carrying scraper, mixer or kneading blades. These blades are yield-

25 able in the arc of a circle against the tension of springs when meeting any large or small obstacle or obstruction which ordinarily would be likely to damage the machine or the blades. Another purpose of my arrange-

30 ment is to obtain a more compact and more efficient machine and to provide a structure in which the springs are fully protected against contact with the materials being mixed, whereby clogging of the springs as

35 well as the possibility of the breaking of the springs when the blades come into contact with extra large obstacles is entirely avoided. My invention will be fully described hereinafter and the features of 40 novelty will be pointed out in the appended claims.

In the accompanying drawings a preferred form of the invention is shown.

Figure 1 is a plan view. Fig. 2 is a 45 vertical section on line A—B of Fig. 1. Fig. 3 is a view of one of the mixing blades with its supporting connection shown in section. Fig. 4 is an elevation of Fig. 3, seen from the side of the blade. Fig. 5 represents in side elevation and plan view the lid of the sleeve which serves for putting the spring under tension.

The mixing apparatus constructed according to this invention essentially consists of 50 mixing blades *a* which move concentrically with the axis of the mixing chamber, of the

mixing blades *b* which execute an eccentric movement, a scraper blade *c* which travels along the inner face of the side wall of the mixing chamber. The three blades *a*, *b*, *c* 60 are mounted upon shafts *d*, *e*, and *f* respectively which are bent at right angles and mounted in sleeves *g*, *h* and *i* respectively. The said sleeves are arranged parallel with the bottom of the mixing chamber, the 65 sleeves *g* and *i* being fixed to the lower surface of a horizontal toothed wheel *k* connected with the driving mechanism of the machine and the sleeves *h* being secured to the arm *l* of the stud *m* mounted in a base 70 of the toothed wheel *k*. In other words the means for operatively connecting each blade or mixing element with the propelling mechanism comprises a member which is rigidly connected with the propelling mechanism 75 and another member movable on said rigid member, one of said members being tubular and forming a protective casing for the other. The movable member is arranged to rock about its own axis on the rigid member 80 and is arranged with said axis located in a plane approximately at right angles to the axis of the propelling mechanism and extending in a direction transverse to the plane of the mixing elements. The latter is 85 attached to the movable member by means of a connection which extends from the movable member in a direction contrary to the travel of the mixing element whereby said mixing element is caused to trail behind the 90 pivot of the movable member and is free to rise upwardly from the mixture under treatment in the mixing receptacle or chamber. The connection with the mixing element is 95 so arranged that the upward rise of said element is substantially in its own plane whereby said mixing element readily yields when encountering an obstacle in said mixture and is thus relieved of all strains which otherwise would result from engagement with such obstacle. The shafts *d*, *e* and *f* are surrounded in the well known manner by spiral springs *n* the ends *n'* of which are fixed in the bottom of the sleeves the other ends *n''* being hooked into removable lids *o*. The lids *o* have at their outer rim a certain 100 number of radial grooves *p* adapted to receive a wedge *q* fixed to the shafts and serving for connecting the shafts with the lids *o* and the springs *n*. The springs *n* continuously push the shafts and consequently the 105 blades against the bottom of the mixing 110

chamber. In order to prevent the blades from touching the bottom of the mixing chamber the lowest position of the blades is limited by stops *r* carried by the sleeve supports against which abut the shafts through the action of the springs *n*. The stops can be regulated by any well known means such as washers or regulating screws so that the distance of the blades from the mixing surface can be regulated.

The tension of the springs *n* can be regulated in the well known manner by turning the lids *o*, said lids being secured in position by means of the wedges *q* which engage with the corresponding groove *p*. The sleeves are further closed at the upper end by caps *s* so that no material can get into the sleeves.

When the blades abut against an obstacle which offers a greater resistance than the tension of the springs *n*, the shafts *d*, *e* and *f* are turned up against the action of the springs *n* as shown in Fig. 4 in dotted lines so that they can slide over the obstacle.

It will be observed that the wedge *q* and the grooves *p* constitute an impositive lock which should the obstacle prove too large to be overcome within the range of the spring would permit the wedge *q* to slide out of its groove to provide a still further yielding of the blade or blades. This however would only occur under extraordinary conditions.

I claim:—

1. A mixing machine comprising a mixing receptacle, a mixing element movable therein, propelling mechanism for actuating said mixing element, a member rigidly connected with said mechanism, a member movable on said rigidly connected member, one of said members covering and protecting the other, said movable member being arranged to rock on its own axis, said axis being located in a plane approximately at right angles to the axis of rotation of said propelling mechanism, and extending also in a direction transverse to the plane of the mixing element and a connection between said movable member and the mixing element whereby said element is free to rise upwardly in substantially its own plane from the mixture under treatment.

2. A mixing machine comprising a mixing receptacle, a mixing element movable therein, propelling mechanism for actuating said mixing element, a member rigidly connected with said mechanism, a member movable on said rigidly connected member, one of said members covering and protecting the other, said movable member being arranged to rock on its own axis, said axis being located in a plane approximately at right angles to the axis of rotation of said propelling mechanism and extending also in a direction transverse to the plane of the mixing element and a connection between the mixing element and a casing carried by said mechanism.

said movable member and the mixing element whereby said element is free to rise upwardly in substantially its own plane from the mixture under treatment, said connection extending from said movable member in a direction contrary to the travel of the moving element to cause the latter to trail behind the pivot of the movable member.

3. A mixing machine comprising a mixing receptacle, a mixing element movable therein, propelling mechanism for actuating said mixing element, a member rigidly connected with said mechanism, a member movable on said rigidly connected member, one of said members being tubular and forming a protective casing for the other, a torsional spring in said casing connected therewith and with the other member, said spring being arranged to resist the rotation of the movable member in a direction away from the mixture under treatment while tending to rotate same in the opposite direction, the movable member being arranged to rock on its own axis, said axis being located in a plane approximately at right angles to the axis of rotation of the propelling mechanism and extending also in a direction transverse to the plane of the mixing element and a connection between said movable member and the mixing element whereby said element is free to rise upwardly in substantially its own plane from the mixture under treatment.

4. A mixing machine comprising a mixing receptacle, a mixing element movable therein, propelling mechanism for actuating said mixing element, a member rigidly connected with said mechanism, a member movable on said rigidly connected member, one of said members being tubular and forming a protective casing for the other, a torsional spring in said casing connected therewith and with the other member, said spring being arranged to resist the rotation of the movable member in a direction away from the mixture under treatment while tending to rotate same in the opposite direction, a stop for limiting the rotation of the movable member in the last named direction, the movable member being arranged to rock on its own axis, said axis being located in a plane approximately at right angles to the axis of rotation of the propelling mechanism and extending also in a direction transverse to the plane of the mixing element, and a connection between said movable member and the mixing element whereby said element is free to rise upwardly in substantially its own plane from the mixture under treatment.

5. A mixing machine comprising a mixing receptacle, a mixing blade movable therein, propelling mechanism for actuating said blade, a casing carried by said mecha-

nism, a shaft connected with the mixing blade and adapted to rock in said casing, a disk rotatably mounted on said casing, an impositive connection between said disk and said shaft and a torsional spring in said casing connected therewith and with said disk, said spring resisting the rocking of said shaft in one direction and tending to rock it in the opposite direction whereby the mixing blade is normally pressed toward the inner surface of said receptacle, said impositive connection between said disk and shaft permitting a rotation of the latter relatively to the spring.

15 6. A mixing machine comprising a mixing receptacle, a mixing blade movable therein, propelling mechanism for actuating said blade, a casing carried by said mechanism, a shaft connected with the mixing

blade and adapted to rock in said casing, a 20 torsional spring in said casing connected therewith, and an impositive connection between said spring and said shaft, said spring resisting the rocking of said shaft in one direction and tending to rock it in the opposite direction whereby said mixing blade is normally pressed toward the inner surface of said receptacle, said impositive connection between said spring and shaft permitting a rotation of the latter relatively to the 30 spring.

In testimony whereof I affix my signature in presence of two witnesses.

GUSTAV EIRICH.
